UNITED STATES PATENT OFFICE

129,379

DESIGN FOR A CHILD'S SEAT FOR BARBER CHAIR

William A. Dennis and Virgil A. Dennis, West Los Angeles, Calif.

Application March 1, 1941, Serial No. 99,278

Term of patent 3½ years

To all whom it may concern:

Be it known that we, William A. Dennis and Virgil A. Dennis, citizens of the United States, residing at West Los Angeles, in the county of Los Angeles and State of California, have invented a new, original, and ornamental Design for a Child's Seat for Barber Chair, of which the following is a specification, reference being had to the accompanying drawing, forming part thereof.

We claim:

The ornamental design for a child's seat for barber chair, as shown.

WILLIAM A. DENNIS.

VIRGIL A. DENNIS.
